UNITED STATES PATENT OFFICE.

WILLIAM C. HUSS, OF CINCINNATI, OHIO, ASSIGNOR TO THE HUSS BROTHERS COMPANY, OF SAME PLACE.

DESIGN FOR A WALL-FIXTURE FOR COUNTERS.

SPECIFICATION forming part of Design No. 22,127, dated January 10, 1893.

Application filed December 15, 1892. Serial No. 455,307. Term of patent 3½ years.

To all whom it may concern:

Be it known that I, WILLIAM C. HUSS, a citizen of the United States, and a resident of Cincinnati, in the county of Hamilton and State of Ohio, have invented a certain new and useful Design for a Wall-Fixture for Counters, of which the following is a specification.

My invention is a new and original design for a wall fixture for counters, the leading features of which are the recessed frieze, the columns supporting the frieze and cornice, the ornamentation and reflecting surfaces as shown in the accompanying drawings, in which:—

15 Figure 1. is a front view of one-half of the fixture made according to my design. Fig. 2. is a vertical transverse section of the same taken through the line $\alpha\alpha$, of Fig. 1.

The side-board or lower portion of the fixture may be of any approved construction and is surmounted by a top A, straight from end to end, covering the side board or closet portion and projecting over the end pedestals A'. Upon this top about mid way between the rear and forward edges are the columns B, three upon each side of the center. The columns have rectangular bases and diagonally ornamented bosses, b. Above the base and between the base and upper carved portion b', the column has vertical beads or flutings b² and the column is surmounted by carved capitals B', which project in nearly a straight line from the top of the column. The sides or faces of the capitals are formed in cyma recta curves to the abacus. Surmounting the end capitals upon each side of the center are pilasters C, which have sunken front panels in the portion which comes upon the frieze. A molding above the frieze and capitals is 40 surmounted by short pilasters, the flat surfaces of which are ornamented with festoons. The frieze D is apparently supported upon

the capitals B' and between the columns at each side of the center is recessed to form the niches E, the upper portion of which is an arched molding e. The arch or canopy of the niche is finished with prismatic reflecting surfaces, preferably of beveled glass. The lower edges rest upon the molding in line with the abacus of the capitals, which molding is curved to conform to the rearwardly curved flat surface e'. The base of the niches is a straight molding f, which extends the entire length of the fixture and is supported by brackets f', the brackets and the molding below them form the upper frame work of the glass or reflecting panels F. The columns next to each of the end columns are centrally provided with carved ornaments g, from which project the brackets g', which are fitted with illuminating globes g². In front of each of the niches are depending ornamental fret work baskets G, within which are illuminating globes, the light from which is reflected by the prismatic arch work of the niches.

The central portion of the frieze H is, for better effect, made of highly polished material or plate, such as onyx. Upon each end, resting with its base upon the column, is a scroll work ornament I of darker material than the base of the frieze or other wood work of the fixture, such as oxidized copper. The center of the plate or panel H, and the frieze between the niches are ornamented with patera of dark material, in strong contrast with the base upon which they are set.

What I claim is

A design for wall fixtures for counters substantially as herein shown and described.

WILLIAM C. HUSS.
